ELECTROMAGNETIC DEVICE

Rolland D. Nelson, Hales Corners, Wis., assignor to Line Material Company, South Milwaukee, Wis., a corporation of Delaware

Original application November 13, 1941, Serial No. 418,876. Divided and this application February 15, 1943, Serial No. 475,907

7 Claims. (Cl. 175—356)

This invention relates to electromagnetic devices such as transformers, chokes, and other devices of this general nature, and is a division of my application filed November 13, 1941, Serial No. 418,876, for Electromagnetic devices.

Transformers have heretofore been made in which wound magnetic cores are employed. However, transformers having wound magnetic cores frequently require a considerable amount of assembly work and often require very great care in order to avoid the danger of imparting mechanical stresses to the magnetic core after the magnetic core has been annealed, as these mechanical stresses adversely affect the magnetic characteristics of the cores thereby resulting in a lowering of the efficiency of the transformer or other electromagnetic device.

This invention is designed to overcome the above noted defects and objects of this invention are to provide a novel form of electromagnetic device which has its core structure formed of wound magnetic ribbon, which is wound into closed cores which are thereafter cut into sections all of which are used in the completed device, in which no unusual care is required in the assembly of the parts of the device, in which no bending, machining, or other working of the core structure is required after annealing, and in which short-circuiting of the laminations is avoided.

The invention in its broadest aspect permits the use of stacked magnetic laminations, or wound cores formed of magnetic ribbon which are subsequently cut into parts after winding, the resulting magnetic core structure being laminated throughout its entire extent.

Further objects are to provide an electromagnetic device in which there are relatively few joints in the core structure, in which the joints in the core structure are so formed that a substantially edge to edge contact of the adjacent laminations is obtained, thereby materially reducing the reluctance of the magnetic path, and in which these results are obtained in a very simple manner and with a very small amount of work required in the manufacture of the device.

Further objects are to provide a novel construction of electromagnetic device in which the losses are relatively small, and in which a very good space factor is obtained for the conducting winding.

Further objects are to provide a novel form of transformer or other electromagnetic device which is extremely simple to manufacture, and

in which the number of operations required in its production is materially reduced.

An embodiment of the invention is shown in the accompanying drawing, in which:

5 Figure 1 is a view, partly in section and partly broken away, showing a transformer.

Figure 2 is a sectional view on the line 2—2 of Figure 1.

In making the transformer, the central core is 10 formed by winding a closed core of magnetic ribbon. This wound magnetic ribbon is then cut in half and the two sections are arranged back to back to form the central core portion 1 provided with outwardly extending end portions 2 projecting outwardly in opposite directions at each end of the central core.

The outer cores are formed of wound magnetic ribbon and are cut in half and the two halves are 15 separated. The half sections forming the outer cores are indicated at 3 and each is provided with inwardly projecting end portions 4 which are spaced apart, as shown most clearly in Figure 2. These end portions 4 abut the side faces of the end portions 2 of the central core section and an 20 edge to edge contact is obtained. It is preferable to grind the adjacent faces of the portions 2 and 4 to secure smooth, even faces and an accurate edge to edge contact. After the grinding has 25 been completed, all of the cores are annealed and any burrs or wire edges that may result from the grinding or cutting are burned off, but if by any 30 chance any remaining burrs or wire edges should be left after annealing, these may be readily removed by means of a wire brush or, in fact, 35 they may be removed by a wire brush prior to annealing.

It is not necessary to grind down the central portion of the central core 1 for it will be seen that the outer cores do not cross over the curved 40 portions at the outer ends of the central core. Instead the outer cores terminate in the portions 4, see Figure 2, which do not cross over the curved outer ends of the central core, see Figure 1.

The wound magnetic ribbons forming the outer 45 and central cores are held clamped during cutting, grinding and annealing operations. Obviously any oxide that may be formed on the ground faces may be scraped off if desired prior to assembly. It is to be distinctly understood, however, that no machining, bending or working of any of the core sections occurs after annealing.

While it is preferred to wind all of the core sections and to cut them in half portions, it is within the province of this invention to form all 50 of the core sections of stacked magnetic lamina-

tions which are shaped as required, though this is not the preferred manner of forming the device.

The central core 1 may be placed in an ordinary winding lathe and the conducting winding 5 is wound thereon, suitable insulation being provided in the customary manner.

The several sections of the core may be clamped together in any desired way. For example, the L-shaped clamping members 6 may be employed and may be drawn towards each other by means of bolts 7, suitable insulating sheets 8 being provided between all of the faces of the clamping members and the laminated core structure.

The material used in the making of the cores is any suitable magnetic ribbon. It is preferable to use silicon steel which may be either hot rolled or cold rolled as this material has been found highly efficient in the manufacture of these transformers or other electromagnetic devices of this general nature, such as chokes for instance.

It will be seen that the lateral edges of the laminations of the central core have an edge to edge contact with the adjacent edges of the outer cores.

It is to be noted that the magnetic flux travels lengthwise of the magnetic ribbon in substantially all portions of the core structure and this is the path having minimum magnetic reluctance due to the manner in which the particles of the magnetic ribbon are orientated during their manufacture. However, there is a small portion of the magnetic path where the flux travels cross-wise of the magnetic ribbon where it passes from the end portions of the central core into the outer cores. This path of cross travel of the flux is very short and is confined to a very limited portion of the entire core structure.

It will be seen, therefore, that transformers and other electromagnetic devices have been disclosed by this invention which have a very small magnetic reluctance for the flux travel and which are extremely simple to make and which utilize the advantages of wound magnetic cores formed from magnetic ribbon, though allowing the conducting winding to be wound in the ordinary simple manner without requiring any special processes for the winding of the conducting winding.

It is to be noted that the substantially edge to edge contact between the laminations of the central and outer cores materially reduces the reluctance of the magnetic path.

It will be seen further that transformers or other electromagnetic devices constructed in accordance with this invention may be made with a very small number of operations and in a very simple manner.

It is to be understood that wherever the expressions "laminations" or "magnetic laminations" are employed, it is intended that these expressions shall not be limited to stacked laminations but shall include any laminated structure whether it is formed by winding magnetic ribbon or by stacking magnetic laminations.

Although this invention has been described in considerable detail, it is to be understood that such description is intended as illustrative rather than limiting, as the invention may be variously embodied and is to be interpreted as claimed.

I claim:

1. A core construction for an electromagnetic device comprising a core formed of magnetic laminations having oppositely extending, outwardly turned end portions at opposite ends

thereof with the outer ends of the end portions spaced apart at each end of said core, and a second core structure formed in two parts of magnetic laminations having inwardly turned end portions whose lateral edges are in close juxtaposition to the lateral edges of the outwardly turned portions of the first mentioned core, the inner ends of the inwardly turned end portions being spaced apart.

10 2. A core construction for an electromagnetic device comprising a core formed of magnetic laminations having oppositely extending, outwardly turned end portions at opposite ends thereof with the outer ends of the end portions spaced apart at each end of said core, and a second core structure formed in two parts of magnetic laminations having separate inwardly turned end portions whose lateral edges are in close juxtaposition to the lateral edges of the 15 outwardly turned portions of the first mentioned core.

20 3. A core construction for an electromagnetic device comprising a central core having two sections of magnetic laminations with the ends turned outwardly in opposite directions at opposite ends of the central core, and an outer core structure comprising magnetic laminations formed in two spaced apart sections on each side of the central core having each section on each 25 side of the central core provided with inwardly turned ends, the inwardly turned ends of each section on opposite sides of the central core having their side faces in close juxtaposition to the side faces of the corresponding outwardly turned portions of the central core.

35 4. A core construction for an electromagnetic device comprising a central core having two sections of magnetic laminations with the ends turned outwardly in opposite directions at opposite ends of the central core, and an outer core structure comprising magnetic laminations formed in two spaced apart sections on each side of the central core having each section on each 40 side of the central core provided with inwardly turned ends, the inwardly turned ends of each section on opposite sides of the central core having their side faces in contact with the side faces of the corresponding outwardly turned portions of the central core with the laminations of the 45 inwardly turned ends of the outer sections having substantially an edge to edge contact with the laminations of the outwardly turned ends of the central core.

50 5. A core construction for an electromagnetic device comprising a central core having two sections of magnetic laminations with the ends turned outwardly in opposite directions at opposite ends of the central core, and an outer core structure comprising magnetic laminations formed in two spaced apart sections on each side of the central core having each section on each 55 side of the central core provided with inwardly turned ends, the inwardly turned ends being located at each end of each section of the outer core structure and being spaced apart, the inwardly turned ends of each section on opposite sides of the central core having their side faces in close juxtaposition to the side faces of the corresponding outwardly turned portions of the central core.

6. A core construction for an electromagnetic device comprising a central core having two sections of magnetic laminations with the ends turned outwardly in opposite directions at opposite ends of the central core, and an outer core

structure comprising magnetic laminations formed in two spaced apart sections on each side of the central core having each section on each side of the central core provided with inwardly turned ends, the inwardly turned ends being located at each end of each section of the outer core structure and being spaced apart, the inwardly turned ends of each section on opposite side of the central core having their side faces in contact with the side faces of the corresponding outwardly turned portions of the central core with the laminations of the inwardly turned ends of the outer sections having substantially an edge to edge contact with the laminations of the outwardly turned ends of the central core.

7. A core construction for an electromagnetic device comprising at least two core sections, each

section consisting of a plurality of layers of flat magnetic ribbons with the flat faces of the ribbons laid one upon the other, each section consisting of a main leg portion and end portions projecting at substantially right angles from the main leg portion and having end faces extending across the end portions and having side faces extending longitudinally of the end portions, said sections being positioned with a side face of each 10 end portion of one section overlapping a side face of the corresponding end portion of the other section, the side edges of the laminations of the end portions of one section being in close proximity to and substantially paralleling the side edges 15 of the laminations of the end portions of the other section.

ROLLAND D. NELSON.
